Patented Nov. 20, 1917.

FIG. 3.

FUG. 1.

Fig. 4.

Inventor.

Eric H. Everett,
By his attorney, Charles D. Gooding.

UNITED STATES PATENT OFFICE.

ERIC H. EWERTZ, OF WOLLASTON, MASSACHUSETTS.

SLED.

1,247,098.

Specification of Letters Patent. Patented Nov. 20, 1917.

Application filed January 20, 1917. Serial No. 143,434.

To all whom it may concern:

Be it known that I, ERIC H. EWERTZ, a citizen of the United States, residing at Wollaston, in the county of Norfolk and 5 State of Massachusetts, have invented new and useful Improvements in Sleds, of which the following is a specification.

This invention relates to improvements in sleds, the object of the invention being to 10 provide a sled which is operated by placing one foot upon the sled and using the other foot to propel said sled by pushing against the surface of the ground, the sled having a single runner and being operated by means 15 of a steering post which is connected to the front end of the runner, so that by operating the steering post the runner may be bent slightly laterally thereof so as to steer the sled and also to maintain the balance of 20 the user of the sled.

The invention consists in the combination and arrangement of parts set forth in the following specification and particularly pointed out in the claims thereof.

25 Referring to the drawings:

Figure 1 is a side elevation, partly in section, of the sled.

Fig. 2 is a plan view of the same with the steering post shown in section.

30 Fig. 3 is a sectional elevation taken on line 3-3 of Fig. 2.

Fig. 4 is a detail sectional plan taken on line 4-4 of Fig. 1.

Like numerals refer to like parts throughout the several views of the drawings.

5 Fig. 5 is the platform of the sled, 6 is the runner and 7 the steering post. The runner consists of a contact member 8, the front end 9 of said runner being curved upwardly and 10 then bent back upon itself along the portion 10 which terminates in an ear 11. The rear end of the runner extends upwardly and forwardly at an angle at 12, thence along the under side of the platform at 13, 15 to which platform it is fastened, and thence downwardly and forwardly at 14 terminating in an ear 15 which is fastened to the contact member 8 of the runner.

The steering post 7 is rotatably mounted 50 on the platform 5 and extends through a sleeve 25. Said sleeve is provided with a horizontal flanged portion 16 which is fastened to the top of the platform 5 and has a flange 17 on its rear end to which a toe-piece 18 is fastened. The toe-piece 18 is 55 preferably open on its upper side and pro-

vided with lacings 19 so that it may lace to fit different size feet.

The upper end of the steering post 7 is provided with a handle 20 by means of 60 which said steering post may be rotated. The lower end of the steering post below the platform 5 is flattened on opposite sides at 21 and this flattened portion extends through a similarly shaped hole provided 65 in a cross-bar 22. Said cross-bar 22 is secured to the steering post 7 by a cross pin 23. The opposite ends of the cross-bar 22 are connected by a pair of links 24 to the ear 11. 70

In using the device, the coaster places his foot upon the platform 5 with the toe of the foot in the toe-piece 18. He grasps the handle 20 firmly with both hands and propels the sled by means of his other foot. To 75 steer the sled and to maintain his balance, he turns the steering post by means of the handle 20 and thus, through the cross-bar 22 and links 24, the runner is sprung to one side or the other, thus securing the desired 80 result of steering the sled and maintaining the balance of the coaster.

Having thus described my invention what I claim and desire by Letters Patent to secure is:

85 1. A sled having, in combination, a platform, a single runner comprising a contact member extended upwardly at its forward end and at its rear end, said rear end extension being fastened to said platform, a cross-bar rotatably mounted on said platform and a pair of links connecting the opposite ends of said cross-bar to the forward end of said runner. 90

2. A sled having, in combination, a platform, a single runner comprising a contact member extended upwardly at its forward end and then backwardly upon itself and terminating in an ear, the rear end of said runner extending upwardly, thence along 100 said platform to which it is fastened and thence downwardly into engagement with said contact member, a cross-bar rotatably mounted upon said platform and a pair of links connecting the opposite ends of said 105 cross-bar to said ear. 95

3. A sled having, in combination, a platform, a single runner comprising a contact member extended upwardly at its forward end, the rear end of said runner extending 110 upwardly and forwardly at an angle to engage said platform, thence extending for-

- wardly along said platform to which it is fastened and thence downwardly and forwardly to engage said contact member, a steering post rotatably mounted on said platform, a cross-bar fast to the lower end of said steering post and a pair of links connecting the opposite ends of said cross-bar to the forward end of said runner.
4. A sled having, in combination, a platform, a single runner comprising a contact member extended upwardly at its forward end and at its rear end, said rear end extension being fastened to said platform, a steering post rotatably mounted on said platform,

form extending upwardly to a substantial distance thereabove and projecting beneath said platform, a cross-bar fast to the lower end of said steering post and a pair of links connecting the opposite ends of said cross-bar to the forward end of said runner.

In testimony whereof I have hereunto set my hand in presence of two subscribing witnesses.

ERIC H. EWERTZ.
